UNITED STATES PATENT OFFICE

120,244

DESIGN FOR A COMBINATION GLASS DESSERT BOWL AND DISH OR ARTICLE OF SIMILAR NATURE

Albert H. Nicholson, Columbus, Ohio, assignor to The Federal Glass Company, Columbus, Ohio, a corporation of Ohio

Application December 27, 1939, Serial No. 89,150

Term of patent 3½ years

To all whom it may concern:

Be it known that I, Albert H. Nicholson, a citizen of the United States of America and a resident of Columbus, in the county of Franklin and State of Ohio, have invented a new, original, and ornamental Design for a Combination Glass Dessert Bowl and Dish or Article of Similar Nature, of which the following is the specification, reference being had to the accompanying drawing forming a part thereof.

I claim:

The ornamental design for a combination glass dessert bowl and dish or article or similar nature, substantially as shown.

ALBERT H. NICHOLSON.
